Des. 203,515

Patented Jan. 18, 1966

203,515

BOWL FOR CITRUS FRUITS

Henry S. Zibelin, 1423 26th St. NW., Winter Haven, Fla.

Filed May 25, 1965, Ser. No. 85,447

Term of patent 14 years

(Cl. D44—15)

Fig. 1

Fig. 2

Fig. 3

Fig. 4

FIGURE 1 is a side elevational view of a bowl for citrus fruits, showing my new design;

FIGURE 2 is a bottom plan view;

FIGURE 3 is a top plan view; and

FIGURE 4 is a fragmentary sectional view taken on line 4—4 of FIGURE 3.

I claim:

The ornamental design for a bowl for citrus fruits, substantially as shown.
